INVENTOR

BY *Victor J. Evans*

ATTORNEY

WITNESS:

George L. Ogle.

UNITED STATES PATENT OFFICE

CORNELIUS B. GEORGE, OF WINCHESTER, KENTUCKY

HOLY WATER FONT

Application filed June 27, 1930. Serial No. 464,347.

This invention relates to new and useful improvements in fonts for religious services and has for the primary object, the provision of a device of the above stated character, whereby sacred or holy water may be dispensed in small quantities, sufficient for religious needs while the remaining water is stored and conserved from evaporation or undue waste, consequently affording a large saving in holy water and obviating the necessity of replenishing the device with water except at long intervals which is extremely advantageous over well known types of fonts wherein the waste and evaporation of the water are very quick.

Another object of this invention is the provision of means for permitting the easy and quick refilling of the reservoir with holy water and which is capable of permitting the dispensing of the water in a few drops at a time when desiring to sprinkle persons when reclining or ill.

A further object of this invention is the provision of a bowl or receptacle in conjunction with the reservoir and having communication therewith, so that a small quantity of water is always maintained therein from the reservoir and will automatically replenish the supply of the water as used from the bowl or evaporated therefrom.

A further object of this invention is the provision of means whereby desired religious symbols or pictures may be applied to the front of the reservoir to provide the device with proper religious significance.

A still further object of this invention is the provision of a font of the above stated character which will be simple, durable and efficient, and which may be manufactured and sold at a comparatively low cost.

With these and other objects in view as will become more apparent as the description proceeds, the invention consists in certain novel features of construction, combination and arrangement of parts as will be herein-after more fully described and claimed.

For a complete understanding of my invention, reference is to be had to the following description and accompanying drawings in which:

Figure 1 is a front elevation illustrating a font constructed in accordance with my invention.

Figure 2 is a vertical transverse sectional view illustrating the same.

Referring in detail to the drawings, the numeral 1 indicates an elongated and vertically disposed reservoir for containing sacred or holy water and the rear wall 2 adjacent the front wall 3 is provided with an indentation 55 or recess 4 defining a substantially hook-shaped flange 6 to be engaged by a hook or other form of support for attaching the reservoir vertically to the wall of the building. The bottom wall 7 of the reservoir 1 is provided with an opening in which is secured a nipple 8 as shown at 9 and the latter is internally screw threaded to receive a screw threaded plug 10 projecting beyond the nipple and reduced and screw threaded to form 60 an attaching end 11 for a closure cap 12. The plug 10 is provided with a restricted bore 65 13 to permit a small quantity of water to be dispensed from the reservoir in drop formation so as to permit the device to be employed as a sprinkler when desiring to 70 sprinkle people in recline or ill or to sprinkle rooms, beds or religious articles. When desiring to fill the reservoir 1 with holy water, the cap 12 and the plug 10 are removed from 75 the nipple 8 thereby providing a comparatively large passage for directing the water into the reservoir.

The bowl 14 is formed integrally with the front wall 15 of the reservoir and is in communication with the interior of the latter by an opening 16 located adjacent the bottom wall 7 for the purpose of permitting the bowl 14 to be automatically supplied with water 80 from the reservoir. With the cap 12 applied to the plug 10, the reservoir is hermetically sealed and the water within the reservoir will pass into the bowl 14 until the height of the water in the bowl is equal to the height of the opening 16 thereby stopping the flow of water 85 into the bowl. With this arrangement a sufficient quantity of water is always maintained in the bowl 14 for religious services, but only in a quantity that will prevent undue waste or evaporation of the holy water.

The front wall 15 of the reservoir 1 adjacent the upper end is provided with a recess 17 to receive a disk or plate 18 bearing suitable religious characters and indicia it being understood that the disk or plate 18 may be manufactured separately from the font and may be made up with different religious characters or indicia and secured in the recess 17 by cement or other suitable securing means to furnish the desired religious symbols of different religions. The front wall 15 is further carved or otherwise ornamented to provide the font with an attractive appearance. The design on the front wall and also the bowl 14 may be varied to suit the requirements.

The device further is constructed in different sizes and may be of such a size that the device can be easily transported and used as a sprinkler in religious services to people who are ill and unable to attend regular church services.

While I have shown and described the preferred embodiment of my invention, it will be understood that minor changes in construction, combination and arrangement of parts may be made without departing from the spirit and scope of the invention as claimed.

Having thus described my invention, what I claim is:

A font comprising a vertically disposed reservoir having the rear wall curved inwardly to provide a recess located adjacent the top wall and co-operating with the edge of said top wall in providing a combined finger grip for carrying the reservoir and a hook to engage a support, a bowl formed on the front wall of the reservoir adjacent the bottom wall and having communication with the interior thereof, an internally screw-threaded nipple secured in the bottom wall of the reservoir, a plug having a restricted passage therethrough threaded in the nipple to permit the fluid of the reservoir to be dispensed in small drops and having one end reduced and screw-threaded and disposed outwardly of the nipple and reservoir, and a cap threaded to the reduced and extended end of the plug.

In testimony whereof I affix my signature.
CORNELIUS B. GEORGE.
